Application November 3, 1953, Serial No. 390,042

8 Claims. (Cl. 33—180)

This invention relates to aircraft propellers and in particular, to measuring equipment by which the pitch setting of aircraft propeller blades may be readily measured while the propeller is installed on an aircraft.

The invention provides a propeller blade protractor assembly which may be used for any or all of the blades of single or dual rotation propellers, enabling accurate determination and correlation of propeller blade pitch angles. On dual rotation propellers, the blades of the outboard propeller may have a slightly different pitch angle setting than the blades of the inboard propeller, and the pitch angle of the blades of an inboard propeller may vary at a different rate than the pitch angle of the blades of the outboard propeller. A proper protractor serves to confirm that the blades, after propeller installation, are properly coordinated for the design pitch settings. Frequently, after installation of a dual rotation propeller, it is desirable to check the propeller pitch angles with respect to a fixed reference.

In the past, some rather complex optical procedures have been utilized to determine blade pitch angles while the propeller was installed on an aircraft. The present invention enables precise determination of blade pitch angles by the use of a protractor assembly which is designed so that a plane perpendicular to the propeller axis is used as a reference plane from which the pitch angle of any propeller blade can be determined with great precision. This obviates the need for using level bubbles, plumb lines, or other references which are not directly associated with the propeller installation.

Objects of the invention are to provide a readily portable propeller blade protractor assembly which may be installed on, and utilized for the determination of the pitch angle of, any propeller blade when its propeller is in operating position in an aircraft. A further object of the invention is to provide a protractor assembly of more or less universal utility, so that, using appropriate adapters, the basic protractor assembly can be used for propeller blades of a wide variety of sizes and designs.

The specific nature and details of the invention can better be appreciated by reading the following detailed description in connection with the attached drawings, in which similar reference characters indicate similar parts, and in which:

Fig. 1 is an elevation of the invention in use on the outboard propeller of a dual rotation propeller system,

Fig. 2 is an elevation similar to Fig. 1 wherein the pitch angle of an inboard propeller blade is being determined,

Fig. 3 shows the invention applied for pitch angle determination on a single rotation propeller,

Fig. 4 is an enlarged plan of the invention adjusted as in Fig. 1 and showing additional details,

Fig. 5 is a section on the line 5—5 of Fig. 4, and

Fig. 6 is a plan of a part of the invention as adjusted for use with an inboard propeller of a dual rotation system.

2

In Figs. 1 and 2, in dotted lines, we show a power plant nose 10 upon the propeller shafts of which are mounted an inboard propeller 12 and an outboard propeller 14. The inboard propeller has blades 16 extending therefrom, and the outboard propeller has blades 18 extending therefrom, the blades as shown having airfoil profile in section.

Referring to Fig. 1, measurement of the pitch angle of the blade 18 involves the measurement of the angle between the chord of the blade and a reference line or plane. An appropriate plane is one which is perpendicular to the axis of rotation of the propellers and which thus lies parallel to the plane of rotation of the propellers, such plane being indicated at 20. Some particular station along the propeller blade is normally specified as one at which pitch angle readings are to be taken. Since any conventional propeller blade twists slightly from its root toward its tip, it is necessary for comparison and standardization to measure the pitch angle of all blades at a standard station, or distance of the blade section from the center of rotation. Before making the pitch angle determination, each blade is appropriately marked to identify the standard station. Thereupon, a protractor assembly 22 is slipped over the end of the propeller blade, the protractor assembly including a member 24 having an aperture 25 to receive the blade. The member 24 includes anvils 26 and 28 which rest on the thrust face of the propeller blade, there also being a stop 30 which is engaged with the leading edge of the propeller blade. A clamp 32 on the member 24 is then screwed down upon the camber surface of the propeller blade so that the member 24 is held firmly, in fixed attitude, relative to the blade.

A member 34 is pivoted to the member 24 at 36, a portion of the member having a vernier scale 38 which registers with angle graduations 40 inscribed on the member 24. The member 34 may be swung on its pivot and may be clamped in any position by a screw clamp 42 operating in conjunction with a slot 44 on the member 24. The member 34 is further provided with a plane plate 46. To determine the pitch angle of the blade 18, the member 34 is moved about its pivot until the plane of the plate 46 is coincident with the plane 20 which is perpendicular to the propeller axis of rotation.

To establish this parallelism relationship between the planes 20 and 46, a member 48 is slipped over the inboard propeller blade 16, the member 48 having an aperture 50 within which the blade is received, and having anvils 52 and a clamp 54 by which the member 48 is firmly secured to the blade 16. To the member 48 is secured a dial indicator 56 whose movable stem 58 is aligned so that it can engage the plate 46 of the assembly 22.

With the protractor 22 installed on the blade 18 and the member 48 installed on the blade 16, the propellers 12 and 14 may be oscillated relative to one another about their axes so that the dial indicator stem 58 moves back and forth along the plate 46. If the dial indicator reading varies during this oscillation, it shows that the plate 46 is not coincident with the plane 20. Thereupon, the member 34 may be moved about the pivot 36 to a position of adjustment where the dial indicator will indicate zero change as it sweeps along the plate 46 during relative oscillation of the two propellers. When this adjustment is reached, the plate 46 lies in a plane perpendicular to the propeller axis and establishes the member 34 as a reference member from which blade pitch readings may be taken. The blade pitch reading is then observed on the angle marks 40 and precise pitch angle is established by using the vernier scale 38. Normally the scales 38 and 40 would be so calibrated that pitch angles of .01° may be ascertained.

The foregoing description relates to the measurement of pitch angles on the outboard propeller of a dual rotation system. To measure the pitch angles on the inboard propeller, as shown in Fig. 2, the member 22 is installed on the inboard blade 16 and the member 48 is installed on the outboard blade 18. The same adjustment procedure is undertaken and when the plate 46 is perpendicular to the propeller axis, the blade pitch angle of the inboard blade 16 may be read on the scales 38, 40.

By installation of the equipment consecutively on the several blades of the propeller, the pitch angle settings of all blades may be ascertained.

For a single rotation propeller, the protractor assembly 22 may be installed as previously described, and the dial indicator 56 may be secured to a bracket 60 secured in any appropriate manner as by a bolt 62 to the engine structure, providing a fixed mounting for the indicator. By oscillating the propeller and adjusting the plate 34 in the manner previously described, an accurate reading of pitch angle for the propeller blade may be had. In this case, the single rotation propeller is numbered 64 and its blades are noted as 66. Otherwise, the components of the assembly 22 may be identical with those previously described.

Referring to Figs. 4-6, details of the protractor assembly are shown. In Figs. 4 and 5, the reference member 48 includes two posts 70 and 72 on opposite sides of the member, the latter being formed from a flat metallic plate. The post 70 carries the clamp 54, and the post 72 carries a clamp 54', each having a pad 74 for engagement with one surface of a propeller blade such as 16. The two clamps enable attachment of the member 48 to the propeller blade without rocking, there being four points of contact of the member 48 with the blade. These points comprise the two anvils 52 and the two pads 74.

The assembly 22, constituted by the members 24 and 34, includes two blocks 78 and 80 secured on opposite sides of the plate member 24, these blocks holding the screw clamps 32 and 32'. The screw clamps carry pads 82 which are engaged with the camber surface of the blade 18, and are opposed by the two anvils 26 and 28 which engage the thrust face of the propeller blade. Thereby, the assembly 24 is securely held on the blade at four points of contact, so that the reference plate 46 may be adjusted so that it lies in parallelism with a plane normal to the propeller axis.

Preferably, the anvils 26 and 28 and the stop 30 are all set up on a template 84 which is clamped to the member 24 by clamps 86. A template 84 is prepared for each type of propeller blade and the appropriate template for the type of blade to be calibrated is installed on the member 24 when a pitch angle measurement is to be made. Individual characteristics of the airfoil section of the propeller blade make it most convenient to use a template such as 84 since the template includes compensations for any angular difference between the chord line of the blade section and the form of the thrust face of the propeller blade, the latter not necessarily being flat.

Fig. 4 shows the template 84 and the clamps 32 and 32' installed on the assembly 22 for use with a propeller rotating in a counterclockwise direction. The template is located by pads 85 permanently fixed on the member 24, and the clamp blocks for clamps 32 and 32' are secured to member 24 at location 87.

When the protractor assembly is to be used for a clockwise rotating propeller assembly, the member 22 must be turned over as shown in Fig. 6. Herein, the template 84 is transferred from its previously described attachment points at locations 85 on the member 24 to another set of attachment points 90 on the opposite side of the aperture 50 in the member. Also, the clamp blocks 78 and 80 are transferred from the original location 87 to a location 92. This enables the anvils 26 and 28 and the leading edge stop 30 of the template 84 to engage the blade section at proper points on and adjacent the thrust face

of the propeller blade 16 so that the relationship of the anvils 26 and 28 is correct, with respect to the chord line of the propeller blade section.

When the assembly 22 is used on an inboard propeller, as shown in Fig. 6, the member 34 is adjusted to bring the plate 46 into a plane normal to the propeller axis. The scales 38 and 40 face toward the propeller hub rather than toward the propeller tip as in Figs. 1, 3 and 4. However, this mode of reading the scales, from the hub side rather than from the blade tip side, injects no difficulty in using the protractor apparatus effectively.

So far as the reference member 48 is concerned, the anvils 52 and the clamp 70 need not be interchanged when such member is shifted from an inboard propeller blade to an outboard propeller blade, since the member 48 is used simply as a stable mounting for the dial indicator 56. It matters little whether the anvils 52 engage the thrust face or the camber face of the blade, so long as the member 48 is held securely on the blade.

The invention has been shown and described as for use when a propeller is fully assembled and mounted, as on a power plant. However, the inventive scope is deemed to include the claimed protractor when used on an uninstalled propeller. For instance, the dial indicator 56

25 may be carried by a blade of a dual rotation propeller when the latter constitutes an integral assembly, or when its components are mounted on a test spindle whose axis is coincident with the propeller axis. Or, the dial indicator could be mounted on the power unit of the propeller 30 which ordinarily is coaxial therewith and rotatable relative thereto. In any utilization, it is feasible to secure the dial indicator on the member 34, and to dispose the plate 46 on the reference structure so that it provides a reference plane normal to the propeller axis of rotation.

35 The invention herein described may be modified in specific form without departing from the spirit or scope of the invention but it will be clear from the foregoing that the pitch angles of propeller blades for either single or dual rotation propellers may be accurately determined 40 by proper use of the several items of equipment which constitute the protractor assembly.

Though a single embodiment of the invention is shown, it is to be understood that the invention may be applied in various forms and in various environments. Changes 45 may be made in the arrangement shown without departing from the spirit of the invention. Reference should be had to the appended claims for definition of the limits of the invention.

What is claimed is:

50 1. A protractor for determining the pitch angle of a propeller blade when rotatably installed on an aircraft, comprising a member clamped to the propeller blade, a second member pivoted to the first member, said two members having interrelated indicia thereon to indicate 55 the relative angular relation therebetween, said second member having a planar reference portion, the second member being adjustable relative to the first member finally to disposed said planar reference portion in a reference plane parallel to the propeller plane of rotation, and an indicator device secured to the aircraft and having a point contactor part in said reference plane and engageable with consecutively with several points on said reference portion as said blade is rotated relative to said aircraft to gauge the alinement of said portion in said reference plane.

60 2. A protractor for determining the setting angle of a blade assembled in a hub journaled for rotation on a structure, comprising a member including clamps for attaching the member to the blade, a second member 65 pivotally mounted on said first member and including at least two base reference points, reference means adapted to be secured to said structure and comprising a point contactor, said second member being adjustable on its pivot to aline said base reference points in the same plane 70 as the contactor of said reference means as said blade and

hub are rotated about the hub axis relative to said structure, said plane defined by said alignment of said base points lying normal to the hub rotational axis, and scale indicia on said members calibrated to enable reading of the relative angularity of said members.

3. A protractor for determining the setting angle of a blade assembled in a hub journaled for rotation on a structure, comprising a member including clamps for attaching the member to the blade, a second member pivotally mounted on said first member and including at least two base reference points, reference means adapted to be secured to said structure and comprising a point contactor, said second member being adjustable on its pivot to aline said base reference points in the same plane as the contactor of said reference means as said blade and hub are rotated about the hub axis relative to said structure, said plane defined by said alignment of said base points lying normal to the hub rotational axis, and scale indicia on said members calibrated to enable reading of the relative angularity of said members, said first member including detachable locating elements to adapt the protractor to a particular form of blade.

4. A protractor for determining the setting angle of a blade assembled in a hub journaled for rotation on a structure, comprising a member including clamps for attaching the member to the blade, a second member pivotally mounted on said first member and including at least two base reference points, reference means adapted to be secured to said structure and comprising a point contactor, said second member being adjustable on its pivot to aline said base reference points in the same plane as the contactor of said reference means as said blade and hub are rotated about the hub axis relative to said structure, said plane defined by said alignment of said base points lying normal to the hub rotational axis, and scale indicia on said members calibrated to enable reading of the relative angularity of said members, said structure comprising in part, another blade axially spaced from the first blade and rotatable in a plane parallel thereto, and said reference means comprising a dial indicator adapted to be secured to said another blade.

5. For use with a dual rotation aircraft propeller comprising coaxial inboard and outboard oppositely rotatable hubs each having pitched blades extending therefrom, a protractor assembly comprising means secured to a blade of one hub carrying a dial indicator whose movable stem is directed toward the plane of rotation of blades of the other hub, a member secured to a blade of the other hub, a second member pivoted to said first member having a surface engageable by the stem of said dial indicator, said second member being adjustable to bring said surface into a plane parallel to the planes of rotation of said blades, and means to indicate the angular relation of said two members.

6. For use with a dual rotation aircraft propeller comprising coaxial inboard and outboard oppositely rotat-

able hubs each having pitched blades extending therefrom, a protractor assembly comprising means secured to a blade of one hub carrying a dial indicator whose movable stem is directed toward the plane of rotation of blades of the other hub, a member secured to a blade of the other hub, a second member pivoted to said first member having a surface engageable by the stem of said dial indicator, said second member being adjustable to bring said surface into a plane parallel to the planes of rotation of said blades, and means to indicate the angular relation of said two members, said first member including a template removably secured thereto which engages the blade at two points along the chord surface and at the leading edge, and clamps on said member engageable with the camber surface of the blade by which the member is secured to the blade.

7. For use with a dual rotation aircraft propeller comprising coaxial inboard and outboard oppositely rotatable hubs each having pitched blades extending therefrom, a protractor assembly comprising means secured to a blade of one hub carrying a dial indicator whose movable stem is directed toward the plane of rotation of blades of the other hub, a member secured to a blade of the other hub, a second member pivoted to said first member having a surface engageable by the stem of said dial indicator, said second member being adjustable to bring said surface into a plane parallel to the planes of rotation of said blades, and means to indicate the angular relation of said two members, said first member including a template removably secured thereto which engages the blade at two points along the chord surface and at the leading edge, and clamps on said member engageable with the camber surface of the blade by which the member is secured to the blade, said template and clamps being movable to alternate mounting positions on said member to hold the member in correct relationship on a propeller blade adapted for opposite rotation.

8. For use with an aircraft propeller comprising a hub having pitched blades extending therefrom and rotatably mounted relative to a structure, a protractor assembly comprising means secured to said structure carrying a dial indicator whose movable stem is directed toward the plane of rotation of blades of the propeller, a member secured to a blade of the propeller, a second member pivoted to said first member having a surface engageable by the stem of said dial indicator, said second member being adjustable to bring said surface into a plane parallel to the plane of rotation of said blades, and means to indicate the angular relation of said two members.
